UNITED STATES PATENT OFFICE.

LUDWIG SAHA, OF CHICAGO, ILLINOIS.

MATCH-BOX.

1,296,123.

Specification of Letters Patent.

Patented Mar. 4, 1919.

Application filed February 16, 1917. Serial No. 148,991.

To all whom it may concern:

Be it known that I, LUDWIG SAHA, a citizen of the United States, residing in the city of Chicago, in the county of Cook and State of Illinois, whose post-office address is #1620 Blue Island avenue, have invented certain new and useful Improvements in Match-Boxes, of which the following is a specification.

10 This invention relates to single delivery match boxes.

Among the objects of this invention is the provision of a single delivery match box which is inexpensive and simple in construction.

Another object is to provide a match box of this type possessing a construction which will normally maintain the discharge end in closed position.

20 In the accompanying drawings, wherein like characters of reference indicate like or corresponding parts in the several views,

Figure 1 shows a developed form of my improved match box showing a single piece 25 stamping.

Fig. 2 is a plan view of the box folded.

Fig. 3 is a bottom view thereof.

Fig. 4 illustrates the discharge end view taken on line 4—4 of Fig. 2.

30 Fig. 5 illustrates the side elevation taken on line 5—5 of Fig. 4.

Fig. 6 is an enlarged detail showing part of the discharge end.

Referring to the drawings, the match box 35 comprises a receptacle 10 of substantially rectangular form provided with a converging single discharge end 11.

In Fig. 1, the dotted lines indicate lines along which the material, which may be of 40 paper, metal or any other suitable material, is bent to form such improved match box 10.

It will be noted that the filling-end portion 12 is provided with the extended flap portion 13 which is formed with the two triangular teeth 14 adapted to engage within the slots 15^A and 15 of side portions 16 and 17.

50 The bottom portion 18 is bent angularly on the curved line 19 to form the converging discharge end 11 and is further provided with the extension 20 of such shape which will fit nicely or coincide with the cut-out 21 of the top portion 22. The cut-out 21 is of sufficient size to permit the ac-

tion of the operator's thumb in successively 55 removing the individual matches after the breaking of the light paper seal 23. It is intended that in use the extension 20 will be torn off on the slightly perforated line 24 thus affording an unobstructed discharge 60 opening.

It will be observed that the side portion 16^A is made shorter in height to clear the slot 15^A, and that wire clips 25 are employed in securing together the two side 65 portions 16^A and 17.

Particular attention is called to the construction of the discharge end.

The side portions 16 and 17 are folded over from approximately points Z and secured with clips 26 so that a portion of the bottom 18 slopes upwardly from the curved line 19 toward the top 22 and thus affords a springlike or resilient action to the inclined bottom so that the center portion of the 70 curved end 24 tends to contact with the top 22 and thus normally retains the discharge opening in partially closed position and prevents any accidental discharge of the 75 matches.

It is understood that the structure shown, which is one embodiment of my invention, may be made of metal with the cover 12—13 hinged. Likewise any other form of fastening or locking means, other than that described and indicated by 14 may be used without departing from the spirit of my invention. Nor do I wish to limit the use of 85 my improved box to matches.

I claim:

1. A box having a converging end with a restricted discharge opening and formed with one of the walls thereof having a portion bent on an arc and extending toward and resiliently engaging a portion of another wall whereby said discharge opening is normally held in closed position.

2. A box having a converging end with a restricted discharge opening and formed with one of the walls thereof having a portion bent on an arc and extending toward and normally resiliently engaging the central portion of an opposite wall, and side walls retaining said bent portion.

3. A box having a converging end with a restricted discharge opening and formed with one of the walls thereof having a portion bent on an arc and extending toward

and normally resiliently engaging an opposite wall and side walls having triangular overlapping portions arranged to retain said bent portion.

- 5 4. A box having a converging end with a restricted discharge opening and formed with one of the walls thereof having an inclined portion bent about an arc and extending toward and resiliently engaging a
- 10 central portion of an opposite wall, and side walls having triangular over-lapping portions arranged to retain said inclined portion.
- 15 5. A box comprising a converging end portion formed with a restricted discharge opening and with the bottom wall thereof having an inclined portion bent about an arc and extending toward and resiliently engaging the top wall, side walls having
- 20 triangular over-lapping portions for retaining said inclined bottom portion, an opening in said top wall adjacent the discharge

end, an extension on said inclined portion having a form coinciding with and adapted to cover said opening in the top wall. 25

6. A box comprising a converging end portion formed with a restricted discharge opening and with the bottom wall thereof having an inclined portion bent about an arc and extending toward and resiliently 30 engaging the top wall, side walls having triangular over-lapping portions for retaining said inclined bottom portion, an opening in said top wall adjacent the discharge end, an extension on said inclined portion having a form coinciding with and adapted to cover said opening in the top wall, slots 35 in said side walls near the filling end, and a cover for the filling end having projections arranged to lock within said slots. 40

In witness whereof, I have hereunto subscribed my name this 10th day of February 1917.

LUDWIG SAHA.
